FIG. 1

FIG. 2

FIG. 3

FIG. 5

FIG. 4

FIG. 6

FIG. 7

FIG. 8

FIG. 9

FIG. 1 is a perspective view of a clinical thermometer showing my new design, the lead cable being fragmentarily shown to indicate indeterminate length;

FIG. 2 is a front elevation of the thermometer housing, the probe member having been omitted for ease of illustration;

FIG. 3 is a side elevation thereof;

FIG. 4 is an elevation taken from the opposite side;

FIG. 5 is a rear elevation thereof;

FIG. 6 is a front elevation of the thermometer probe, which is illustrated separately for clarity of illustration;

FIG. 7 is a side elevation thereof;

FIG. 8 is a rear elevation thereof; and

FIG. 9 is a bottom plan view thereof.

The dominant features of my design reside in the portions shown in full lines.

A portion of the connecting wire has been omitted from FIG. 1, the probe component has been omitted from FIGS. 2 to 5, inclusive, and the instrument component has been removed from FIGS. 6 to 9, inclusive.

I claim:

The ornamental design for a clinical thermometer, as shown and described.
